LOCK CLASP FOR JEWELS AND SIMILAR ARTICLES

Gerard Desouches, Paris, France, assignor to Cartier, Societe Anonyme, Paris, France, a company of France

Application May 3, 1932, Serial No. 608,926, and in France May 5, 1931

7 Claims. (Cl. 24—201)

There are clasps for ladies' handbags in which one of the branches carries at its end a stationary ball, while the other branch is provided with two contiguous balls adapted to move transversally and maintained in contact with each other by the elastic pressure of a spring. The clasp is closed by bringing the branch that carries the stationary ball over the two contiguous balls of the other branch and by forcing it between said balls which are moved apart and then brought back into contact with each other by the action of the spring, thus locking the branch that carries only one ball. In that closed position, the three balls are disposed at the apexes of a triangle, and are maintained in contact only by the action of the spring.

The object of the present invention is to provide an improved clasp of that type, in which the branch that carries only one ball is provided with a locking device, so that said branch cannot be released under the action of some shock or stress, either by overcoming the elastic pressure that maintains it in position, or because the tension of the spring is no longer sufficient, or said spring is out of order.

Said locking device consists of a tail provided under the single ball and which cooperates with a simple or double push piece, in such manner that the opening of the clasp necessitates the operation of said push piece.

My invention also includes the provision of a spring plate, or any other elastic organ, which is deformed by the tail of the single ball when the latter is brought into the position that closes the clasp. Said spring automatically produces the release of said ball and the opening of the clasp when the push piece is acted upon, or at least facilitates that release.

A preferred embodiment of my invention will be hereinafter described with reference to the accompanying drawing, given merely by way of example, and in which:

Figs. 1 and 2 show the respective branches of the clasp in the open position;

Fig. 3 is a plan view corresponding to Fig. 1, the balls being shown in dotted lines;

Fig. 4 is a front view corresponding to Fig. 2;

Fig. 5 shows the clasp in the closed position partly in section on the line 5—5 of Fig. 3;

Fig. 6 is a front view corresponding to Fig. 5 partly in section on the line 6—6 of Fig. 5;

Fig. 7 is a bottom view of the clasps corresponding to Fig. 5;

Fig. 8 is a front view corresponding to Fig. 1 and showing, in a diagrammatical manner, the mounting of the movable balls.

Fig. 9 shows the push pieces of Fig. 3 in detail.

As shown in the drawing, the clasp, which is supposed in the example to be fitted to the ends of a bracelet *a*, comprises, in the known manner,

on the one hand a branch *b*¹, carrying at one end a ball *c*¹ and pivotally mounted at the other end *d* on the fastener *e* through which said branch *b*¹ is fixed to one end of the bracelet. The other part of the clasp consists of a double branch *b*², *b*³, which carries, through the medium of a cross member *f*, two balls *c*², *c*³ pivotally mounted at *i* in said cross member in the known manner (Fig. 8). In order to preclude the inadvertent movement of said balls away from each other, said balls are kept in contact with each other by the elastic pressure exerted by a spring *g* acting on parts *h* integral with said balls (Fig. 8).

The double branch *b*², *b*³ is mounted on a fastener *k* fixed to the other end of bracelet *a* in any suitable manner.

A tail *l* provided with two opposite notches *m*, is fixed to or soldered to or integral with the under face of stationary ball *c*¹, as shown in Fig. 2, said tail is adapted to engage a hole *n* provided in a cup shaped piece *o* fixed to the fastener *k*. Said cup-shaped piece *o* is adapted to receive the base *p* of ball *c*¹. The cup-shaped piece *o* is provided with a longitudinal slot *o*¹ in which branch *b*¹ engages. Under said cup-shaped piece, there is provided, in fastener *k*, a double push piece *q*¹, *q*² the outer ends of which project laterally from the sides of the fastener *k*, while the inner ends *r*¹, *r*² thereof project under hole *n*, as shown in Figs. 3 and 9. Under cup-shaped piece *o*, there is also provided in fastener *k* springs *t*¹, *t*² adapted to cooperate with said push piece.

Under these conditions, when the clasp is to be closed, branch *b*¹, together with its ball *c*¹, is brought over the two balls *c*², *c*³, in the direction of arrow *F*, (Figs. 1 and 2), and said branch is forced down between said balls, so as to move them apart, which is possible due to their elastic mounting. When balls *c*², *c*³ come back to their initial position, branch *b*¹ is kept enclosed between them, as shown in dotted lines in Fig. 8. Moreover, the tail *l* of ball *c*¹ has thus been engaged into hole *n* (Fig. 3) so as to interlock with push-pieces *q*¹, *q*² the ends *r*¹, *r*² of which penetrate into the lateral notches *m* of said tail. Thus, ball *c*¹ is now locked in position and the clasp cannot open by itself.

Under tail *l* is disposed a spring plate or strip *u*, the ends of which are freely engaged in two housings *v* (Fig. 7), provided in fastener *k*, so that when tail *l* is forced into the closed position its end bears against said spring *u* and deforms it.

The opening of the clasp is effected by pushing in the two push pieces *q*¹, *q*², so as to disengage their edges *r*¹, *r*² from the notches *m* of tail *l*, which is then slightly lifted by spring *u* previously deformed, so that the tail is always disengaged when the push pieces are released. Branch *b*¹ is now unlocked, and it is possible to remove it

in a direction opposite to that of arrow F, so as to open the clasp.

I can, of course, by giving spring u or any other similar elastic organ a suitable tension, obtain, if desired, the automatic opening of the clasp, that is the removal of branch b¹ from between balls c² and c³ by merely depressing push-pieces q¹, q², the opening being then completed by the action of spring u.

10 Obviously the balls have been shown in the preceding embodiment as a mere example of the ornamental members that serve to hold the branches of the clasp together. Other elements could be used for that purpose such as precious stones.

15 While I have disclosed what I deem to be a preferred embodiment of my invention, it should be well understood that I do not wish to be limited thereto as there might be changes made in 20 the arrangement, disposition and form of the parts without departing from the principle of my invention as comprehended within the scope of the appended claims.

What I claim is:

25 1. A clasp of the type described, which comprises in combination, a branch for said clasp, two ornamental members elastically mounted on said branch so that they are normally in contact with each other but can be forced apart, another branch for said clasp, an ornamental member rigidly secured to the last mentioned branch so that the last mentioned ornamental member can be brought into contact with the two first mentioned ornamental members by forcing 30 the second mentioned branch between the two first mentioned ornamental members, and locking means for fixing the last mentioned ornamental member to the first mentioned branch.

40 2. A clasp of the type described, which comprises in combination, a branch for said clasp, two balls elastically mounted on said branch so that they are normally in contact with each other but can be forced apart, another branch for said clasp, a ball rigidly secured to the last mentioned branch, so that the last mentioned ball can be brought into contact with the two first mentioned ones by forcing the second mentioned branch between the two first mentioned balls, and locking means for fixing the last mentioned ball 45 to the first mentioned branch when the parts are so engaged.

50 3. A clasp of the type described, which comprises in combination, a branch for said clasp, two balls elastically mounted on said branch so that they are normally in contact with each other but can be forced apart, a cup shaped piece secured to said branch and provided with a hole, at least one push piece elastically mounted under 55 said cup-shaped piece so that its inner end normally projects into said hole, but can be withdrawn therefrom, another branch for said clasp, a ball rigidly secured to the last mentioned branch, so that the last mentioned ball can be placed in contact with the two first mentioned ones by forcing the second mentioned branch between the two first mentioned balls, and a tail on the under face of the last mentioned ball adapted to engage into said hole, said tail being provided with at least one notch adapted to receive the edge of said push piece that projects into 60 said hole.

70 4. A clasp of the type described, which com-

prises in combination, a branch for said clasp, a fastener for said branch, two balls elastically pivoted on said branch so that they are normally in contact with each other but can be forced apart, a cup-shaped piece fixed to said fastener, said piece being provided with a hole and with a slot, two slideable push pieces elastically mounted in said fastener under said cup-shaped piece on either side of said hole so that their inner edges normally project into said hole but can be withdrawn therefrom, another branch for said clasp, a fastener for the last mentioned branch pivotally connected thereto, a ball rigidly secured to the end of the last mentioned branch, the inner face of the last mentioned ball being adapted to fit in said cup-shaped piece, while the last mentioned branch is adapted to fit in the slot provided in said piece, and a tail on the under face of the last mentioned ball adapted to engage into the hole provided in said cup-shaped piece, said tail being provided with two notches adapted to cooperate with the edges of said push pieces respectively for locking the parts in position.

5. A clasp according to claim 4 further comprising a spring plate mounted in the first mentioned fastener under said hole so as to be brought into contact with said tail when the clasp is being closed, whereby said tail is subjected to an elastic pressure tending to push it outside from said hole.

6. A clasp of the type described, which comprises in combination, a branch for said clasp, two ornamental members mounted on said branch so that they can move with respect to each other, another branch for said clasp, an ornamental member rigidly secured to the last mentioned branch, elastic means on the first mentioned branch for normally maintaining the two first mentioned ornamental members in contact with each other, means for limiting the displacement of said two first mentioned ornamental members away from each other so that the second mentioned branch can be forced between them but the third mentioned ornamental member cannot be forced past them, and locking means for fixing the third ornamental member to the first mentioned branch, whereby the third mentioned ornamental member can be brought into contact with the two first mentioned ornamental members by forcing the second branch between the two first ornamental members, and the parts locked in that position.

7. A clasp of the type described, which comprises in combination, a branch for said clasp, two balls mounted on said branch so that they can be moved with respect to each other, another branch for said clasp, a ball rigidly secured to the last mentioned branch, elastic means on the first mentioned branch for normally maintaining the two first mentioned balls in contact with each other, means for limiting the displacements of the two first mentioned balls away from each other so that the second mentioned branch can be forced between them but the third mentioned ball cannot be forced past them, and locking means for fixing the third mentioned ball to the first mentioned branch, whereby the third mentioned ball can be brought into contact with the two first mentioned balls by forcing the second branch between the two first mentioned balls, and the parts locked in position.

GERARD DESOUCHES.
